(57) **CLAIM**

The ornamental design for a golf club cleaning apparatus, as shown and described.

DESCRIPTION

FIG. 1 is a perspective front, left side view of a golf club cleaning apparatus;

FIG. 2 is a perspective back, right side view thereof;

FIG. 3 is a front view thereof;

FIG. 4 is a left side view thereof;

FIG. 5 is a back side view thereof;

FIG. 6 is a top view thereof; and,

FIG. 7 is a bottom view thereof.

The broken lines in the drawing depict parts of the golf club cleaning apparatus that form no part of the claimed design.
